[57] CLAIM

The ornamental design for combined nut cracker and nut/shell container, as shown and described.

DESCRIPTION

FIG. 1 is a perspective view of a combined nut cracker
and nut/shell container showing our new design;

FIG. 2 is a top plan view thereof;

FIG. 3 is a right side elevation view thereof, the opposite side being a mirror image;

FIG. 4 is a front elevation view thereof;

FIG. 5 is a rear elevation view thereof; and,

FIG. 6 is a bottom plan view thereof.
